UNITED STATES PATENT OFFICE

FRANKLIN H. HART, OF NEW HAVEN, AND WILLIAM A. CARMICHAEL, OF HAMDEN, CONNECTICUT, ASSIGNORS TO C. COWLES & COMPANY, OF NEW HAVEN, CONNECTICUT, A CORPORATION OF CONNECTICUT

LOCKER-DOOR LOCK

Application filed July 12, 1927. Serial No. 205,107.

This invention relates to a locker lock and latch operating means, and has for an object to provide improved lock and latch operating means for this type of devices which will be very simple in construction and may be manufactured and assembled at low cost, and also which will be of rugged construction so that it is not easily gotten out of order or broken.

10 It is also an object of the invention to provide an improved locking means for a latch operating mechanism for this type of devices.

With the foregoing and other objects in view, we have devised the construction illustrated in the accompanying drawings forming a part of this specification, similar reference characters being employed throughout the various figures to indicate corresponding elements. In these drawings,

20 Fig. 1 is a vertical section through our improved lock showing it as applied to a locker door.

Fig. 2 is a rear elevation of the same.

Fig. 3 is a section substantially on line 3—3 25 of Fig. 1 and on a somewhat enlarged scale.

Fig. 4 is a transverse section substantially on line 4—4 of Fig. 1.

Fig. 5 is an elevation of a latch operating lever.

30 Fig. 6 is a detail section showing the means for securing the tumbler barrel in the lock.

Fig. 7 is a side elevation of the tube enclosing the barrel.

Fig. 8 is an end view looking from the left 35 of Fig. 7.

Fig. 9 is an end view looking from the right of Fig. 7.

Fig. 10 is a section similar to Fig. 1 showing a slightly different construction.

40 Fig. 11 is a partial rear elevation and a partial section substantially on line 12—12 of Fig. 10.

Fig. 12 is a section on the same plane on an enlarged scale but showing the bolt in the 45 unlocked position, and

Fig. 13 is a detail elevation.

Referring to Figs. 1 to 9 a locker door is indicated at 15 of any suitable construction, as heavy sheet metal, and carrying on its rear surface suitable guides 16, and a lock or

latch bar 17 adapted to project behind the flange 18 of a frame member or bar 19 to hold the door closed. The bar 17 carries a laterally extending flange or lug 20 having an opening for the rounded head 21 of an 55 operating lever or arm 22. This arm has a non-circular opening 23 to receive a similarly shaped shoulder portion 24 of a tubular member 25, in the present construction the tubular member being flattened on its opposite 60 sides.

Extending through an opening in the door 15 is a tubular sleeve 26 embracing the tubular member 25 and in which this member may turn or the sleeve may turn in the door. The 65 member 25 has a reduced portion 27 having a bearing in a strap 28. This strap is substantially U-shaped and is secured at its opposite ends to the rear of the door by any suitable means, such as rivets 29, and it embraces the inner end of the sleeve 26. The reduced portion 27 forms a shoulder which limits the inward movement of the member 25 by engagement with the inner side of the strap 28. Outward movement of this member is prevented by a collar 30 pinned to a reduced end of the member 25 inwardly of the strap 28, the pin being shown at 31.

Mounted to rotate within the tubular member 25 is a barrel 32 carrying any suitable 80 number of tumbler pins 33 which are controlled by a key 34. These pins are mounted to extend transversely of the barrel and have side lugs 35 to engage the side of the key for positioning the pins and which are engaged by the springs 36 to project one end of the pins when the key is removed from the barrel. The tubular member 25 is provided with longitudinal slots 37, 38 and 39 into which the ends of the pins may project for locking the barrel against rotation relative to the member. The member 25 is also provided with transverse openings 40 for a sliding bolt 41. This bolt is preferably square or rectangular and the opening is substantially the same shape so as to prevent turning of the bolt. In one side of the bolt is a recess 42 to receive an operating pin 43 carried by the inner end of the barrel 32, and it is eccentrically arranged on the barrel so that as 95 100

the barrel is rotated this pin acting in the recess will slide the bolt 41 in its opening. The barrel may be provided with a groove 44 to receive a transverse pin 45 passing through the walls of the member 25 to retain the barrel in position. The bolt 41 is preferably of a thickness to extend into both the strap 28 and the arm 22, the opening 40 being in alignment with both of these elements, as shown in Fig. 1. The arm 22, therefore, has a notch 46 to receive the end of this bolt and the strap 28 has a similar notch 47 leading from the bearing for the reduced portion 27 of the member 25. The strap 28 also has at one side of this notch 47 another notch 48 which is of less depth so as to form a stop shoulder 49.

In operation when the arm 22 is in the position of Figs. 1 and 2 the latch bar 17 is in its holding position behind the flange 18 and the end of the bolt 41 may be projected into the notches 46 and 47 which are in alignment when the arm is in this position. It is, of course, understood that insertion of the key into the slot in the barrel will withdraw the tumbler pins 33 from whichever slot 37, 38 or 39 in member 25 they may be, permitting the barrel to be rotated by means of the key to operate the bolt 41, and then when the key is withdrawn these pins will be forced by the springs 36 outwardly to bring one end of these pins into one of the slots in the member 25 depending on the position of the barrel. The barrel is then held against rotation in the member 25, and if the end of the bolt 41 projects into notches 46 and 47 the arm 22 is locked in this position because the notch 47 is in the stationary strap 28. Therefore, the bar 17 is held in locked position. If the key is withdrawn the arm and its operating mechanism is locked in this position because the barrel is then held against rotation in the member 25 by the tumbler pins 33 entering one of the slots 37, 38 or 39 in the member 25. If it is desired to unlock the door insertion of the key will again withdraw the tumbler pins 33 from the slots in the member 25 permitting rotation of the barrel and withdrawal of the bolt 41 from the notches 46 and 47. The member 25 may then be turned to swing the arm 22 to the dotted position of Fig. 2. However, as a portion of the bolt 41 still projects above the surface of the reduced portion 27 of the member 25 this movement is limited by engagement of the bolt with the shoulder 49 on one side of the short notch 48 in the strap 28. The tubular member 25 may be turned to operate the latch and arm 22 by means of a handle or knob 50 secured to the outer end of the member 25. For manufacturing purposes this knob is shown separate from the sleeve 26 but they may if desired be made in one piece.

From the foregoing it will be apparent that while projecting or retracting the locking bolt 41 the barrel 32 is rotated relative

to the tubular member 25, but while swinging the arm 22 to operate the latch bar 17 the barrel 32 and the tubular member 25 turn together, and in reality they are held against rotation when locked by engagement of the bolt 41 in the notch 47 in the stationary strap 28. The notch 46 for the bolt in the arm 22 is, therefore, not absolutely necessary as this arm is secured to the member 25, but use of this notch is preferred as it permits the use of a thicker, stronger bolt and the bolt also assists in preventing turning of arm 22 on member 25 when the bolt is in the locking position.

In the form shown in Figs. 10 to 13 the strap 28 is omitted, therefore the locking action is made directly with the door 15. In this construction there is a tubular member 51 corresponding to the member 25 in the first form which is mounted to rotate in opening 52 in the door. This opening has a notch 53 and a shorter notch 54 at one side of the first notch to provide a shoulder 55. The member 51 is reduced at 55 to pass through the opening in the door and form a shoulder 56 on the member 51 to engage the front surface of the door and limit the inward movement of this member. This member has a transverse opening for the sliding bolt 57 which opening is in alignment with the door 51 so that when the bolt is projected, as shown in Fig. 11, its outer end will seat in the notch 52 and lock the member 51 against rotation. When the bolt is withdrawn into the member 51 it will be withdrawn from the notch 52 but it will project sufficiently above the surface of the reduced portion 55 so that it may project into the short notch 53 and engage the shoulder 54 to limit the swinging movements of the member 51 and the latch operating arm 58. In this construction the inner end of the member 51 is flattened off on opposite sides at 59 to provide a non-circular portion to project into a similarly shaped opening in the arm 58 so that the arm is secured to turn with this member 51. The arm is held on the member by means of a collar 60 secured to the member 51 by the pin 61. In this construction, as the member 51 has no bearing to the rear of the door, as has member 25 in the first form, an escutcheon or collar 62 is provided extending outwardly from the door and forming a bearing 63 at its outer end for the member 51. This collar or escutcheon is secured to the door by any suitable means, such as rivets 64. The member 51 may be operated to operate the latch by a handle or a knob 65 the same as in the first form, and it will, of course, be understood that the bolt 57 is operated by a key controlled barrel 32 the same as in the first form.

It will be noted that this latch or lock is especially adapted for use in steel lockers, although it is not necessarily limited to use

for this purpose. It is of a very simple and rugged construction, may be easily assembled and will be very reliable in operation.

Having thus set forth the nature of our invention, what we claim is:

1. In a lock, a rotatable member adapted to pass through an opening in a door and having a non-circular portion to receive a latch operating member, a slideable locking bolt carried by said first member, a member carried by said first member for operating the bolt, key controlled means carried by the bolt operating member, means cooperating with the key controlled means to lock the bolt operating member in different positions when the key is withdrawn, and a knob carried by said first member for operating it.

2. In a lock, a rotatable member having a transverse opening, a locking bolt mounted to slide in said opening and to project from the side of said member, a stationary member having an opening to receive the first member, said opening including a notch in one side to receive the bolt to lock the member against turning and also including a shorter notch providing a shoulder to engage the bolt and limit turning movement of the first member in one direction, a latch operating member carried by the first member, and key controlled means for operating the bolt carried by the first member.

3. In combination, a door, a cylindrical member extending through said door and mounted to turn therein, a strap secured to the rear of the door provided with an opening, said member having a bearing in said opening, said opening including a notch in one side thereof, a transversely slideable bolt carried by said member, shoulders on the member cooperating with walls carried by the door to prevent longitudinal movement of the member and secure it in position in the door, a rotatable barrel carried by the said member and having operative connection with the bolt, key controlled means carried by the barrel and cooperating with shoulders on the first member to prevent turning of the barrel, a latch operating member carried by the first member, and a knob for operating the said members.

4. In combination, a sheet metal door, a stationary strap secured to the rear of said door, a cylindrical member having bearings in the door and strap, shoulders on the member cooperating with the strap to prevent longitudinal movement of said member, said strap having a notch extending from one side of its bearing opening and a shorter notch at one side thereof forming a shoulder, a transversely slideable bolt carried by the first member adapted to project into said first notch to lock said member against turning and to engage the shoulder of the second notch when retracted to limit turning movement of the member, key controlled means

carried by the first member for operating the bolt, and a latch operating member connected to the first member.

5. In a lock, a substantially cylindrical member having a tubular outer portion provided with laterally spaced longitudinally extending slots, a cylindrical barrel mounted in said tubular portion and carrying key controlled locking pins adapted to project into said slots to lock the barrel in different positions against turning, a transversely slideable bolt carried by the first member, an operative connection between the barrel and the bolt, a stationary member having an opening forming a bearing for the first member and having a notch in one side of said opening in position to receive said bolt to lock the first member against turning, and a latch operating member connected to the first member.

6. In combination, a door, a stationary strap secured to the rear of the door, said strap having an opening forming a bearing and a notch extending from one side of said opening, a cylindrical member having a bearing in said opening, a latch operating arm carried by said member at one side of the strap, said arm having an opening to receive said member and a notch at one side of said opening similar to that in the strap, a transversely movable bolt carried by said member of a size and arranged to project into both of said notches in one position to lock the arm against movement, means for turning the member, and key controlled means carried by the member for operating the bolt.

In testimony whereof we affix our signatures.

FRANKLIN H. HART.
